(57) **CLAIM**

The ornamental design for a remote control, as shown and described.

DESCRIPTION

FIG. 1 is a perspective view of a remote control according to the present invention;

FIG. 2 is a front elevation view thereof;

FIG. 3 is a rear elevation view thereof;

FIG. 4 is a left side view thereof, a right side view being mirror image thereof;

FIG. 5 is an enlarged top plan view thereof;

FIG. 6 is an enlarged bottom plan view thereof; and,

FIG. 7 is an enlarged fragmentary cross-sectional view taken along lines 7-7 of FIG. 2.

The long-dash short-dash broken lines in FIG. 2 indicate the cut line of the cross-sectional view and form no part of the claimed design. The dash-dash broken lines illustrate portions of the remote control that form no part of the claimed design.
